DESIGN FOR A COMBINED COMB AND RECEPTACLE

Joseph Oriolo, Bergenfield, N. J., and Mercedes
Shull, Scarsdale, N. Y.

Application January 28, 1947, Serial No. 136,466

Term of patent 3½ years

(Cl. D86—8)

To all whom it may concern:

Be it known that we, Joseph Oriolo and Mercedes Shull, respectively citizens of the United States and residents respectively of the county of Bergen, city of Bergenfield, State of New Jersey, and county of Westchester, city of Scarsdale, State of New York, have invented a new, original, and ornamental Design for Combined Comb and Receptacle, of which the following is a specification, reference being had to the accompanying drawing, forming part thereof, in which:

Fig. 1 is a side view of a combined comb and receptacle, embodying our design.

Fig. 2 is a plan view of the above, partially disassembled.

Fig. 3 is an end view of Fig. 2, looking in the direction of the arrows 3—3, and

Fig. 4 is an end view of Fig. 2, looking in the direction of the arrows 4—4.

We claim:

The ornamental design for a combined comb and receptacle, as shown.

JOSEPH ORIOLO.
MERCEDES SHULL.
